UNITED STATES PATENT OFFICE.

WALTER P. MURPHY, OF CHICAGO, ILLINOIS.

METAL CAR-ROOF.

1,156,616.

Specification of Letters Patent. Patented Oct. 12, 1915.

Application filed December 22, 1911, Serial No. 667,297. Renewed March 13, 1915. Serial No. 14,230.

To all whom it may concern:

Be it known that I, WALTER P. MURPHY, a citizen of the United States, and a resident of the city of Chicago, in the county of Cook and State of Illinois, have invented 5 a new and useful Improvement in Metal Car-Roofs, of which the following is a specification.

My invention relates to outside car roofs 10 for freight cars, and comprises metal roof sheets extending from the ridge to the eaves, loosely supported directly on a steel substructure consisting of shallow carlines and purlins rigidly secured together, and connected by flexible watertight joints.

15 The object of my invention is the production of an all steel car roof of minimum weight and thickness which shall be water tight, which shall withstand the wear and tear of service, and which shall be easily repaired or renewed.

20 Further objects of my invention will appear in connection with the description of the embodiment thereof shown in the accompanying drawings.

25 What I consider to be my invention will be more particularly pointed out in the claims.

In the drawings, in which like characters 30 designate like parts wherever they occur, Figure 1 is a top plan view of a part of a car roof embodying my invention, partly broken away to show the roof substructure; Fig. 2 is a side elevation of the same on a 35 larger scale; Fig. 3 is a vertical transverse section through the car on the line 3—3 in Fig. 1 to the same scale as Fig. 2; Fig. 4 is an enlarged vertical section on the line 4—4 in Fig. 1; Fig. 5 is an enlarged side 40 elevation of an eaves cap and part of the car at the eaves; Fig. 6 is an enlarged top plan of a ridge corner cap and part of the roof covering adjacent thereto; Fig. 7 is an enlarged vertical transverse section of the 45 car at the ridge on the line 7—7 in Fig. 6 showing the running board saddle in elevation; Fig. 8 is an enlarged transverse section of the car at the eaves on the line 8—8 in Fig. 5; Fig. 9 is a perspective view of a 50 roof sheet; Fig. 10 is a view similar to Fig. 4 showing modifications of roof sheet and seam cover at a joint; Fig. 11 is a view similar to Fig. 5 showing the modified forms of roof sheet and seam cover of Fig. 10 in side 55 elevation; Fig. 12 is an enlarged transverse section through the car at the eaves showing the modifications of Fig. 10; and Fig. 13 is a perspective view of the modified form of sheet of Fig. 10.

Referring to Figs. 1 to 9, inclusive, my roof is shown applied to an ordinary box car having wooden side and end plates 1, 2, and wooden side and end sheathing 3, 4, and comprises metal roof sheets supported on an all steel substructure. This substructure consists of channel carlines 5 which extend from side plate to side plate and are securely bolted thereto at their ends 6, which are bent down outside of the side plates. The carlines are arranged with their webs up- 60 permost, and have lateral base flanges 7 parallel to the webs and extending outward along the lower extremities of the side flanges or walls. To the base flanges 7 are secured metal purlins 8 extending lengthwise of the car, and which may be continuous from end to end of the car. At the center-line of the car, a metal ridge piece 9, of substantially the same cross-section as the carlines, is arranged lengthwise of the car 65 upon the top webs of the carlines with its base flanges 10 in contact therewith and secured thereto. The purlins are flanged up between the carlines, and the tops of the flanges support sheet-metal roof sheets 11 70 out of contact with the base flanges of the carlines. The roof sheets extend from eaves to ridge of the car and have their side and ridge margins 12 and 13 turned upwardly and their eaves margins 14 turned down- 75 wardly. They are arranged upon the tops of the purlins and base flanges of the ridge-piece with their upturned side and ridge margins adjacent to the sides of the carlines and ridge piece respectively, and with 80 their downturned eaves margins overhanging the fasciae 15 at the eaves of the car. The corners where the upturned margins of each roof sheet come together are formed solid, and the extremities of these upturned 85 margins, except at the corners, are rebent inwardly and downwardly forming protecting lips 16 along the side and ridge edges of the sheets which lie adjacent to the sides of the carlines and the ridge piece, respectively. Corrugations 17, are formed in the sheets parallel with the upturned marginal flanges and at a short distance from them. Seam covers 18, and ridge covers 19, having a flat top portion and downward and 90 outward sloping sides 20, 21 terminating in lateral flanges 22, 23 are arranged longitudinally 95 of the roof sheets.

100

105

110

dinally upon the tops of the carlines and ridge piece respectively, with the ridge seam covers covering the inner ends of the side seam covers. The seam covers project on each side of the ridge piece and carlines to cover the adjacent upturned flanges of the roof sheets, and the lateral flanges 22 and 23 of the seam covers rest flat on the roof sheets between their upturned flanges and corrugations, as clearly shown in Figs. 3 and 4. This arrangement of roof sheets and seam covers provides a non-rigid but water tight joint, as water blown across the roof will be deflected upwardly by the corrugations 17 and sloping sides of the seam covers and pass over the latter and off the roof. Any water finding its way under the flanges of the side seam covers will be arrested by the upstanding marginal flanges on the roof sheets, and will pass along the space between these flanges and the seam covers and off the eaves.

The side seam covers are secured at the eaves by means of eaves caps 24 riveted thereto and bolted to the fasciae and side plates below the eaves. These eaves caps have projections 25 on their under sides which rest on top of the fasciae to insure that the eaves caps shall be properly spaced above the fasciae to avoid pinching the corners of the roof sheets, which are turned down between the eaves caps and fasciae. Holes 26 are left in the walls of the eaves caps below the eaves to allow water running down between the marginal flanges of the roof sheets and seam covers to pass off the eaves, and to prevent cinders from collecting in the space between the eaves caps and fasciae. Clips 27 bearing lightly on the roof sheets are used to secure the latter at the eaves between the eaves caps. Ridge corner caps 28 of sheet metal, shaped to conform to the side seam covers and ridge seam covers at their intersection, are fitted over the ridge and side seam covers at the ridge corners of the sheets and serve to secure the latter at the ridge. The side seam covers stop short of the ridge marginal flanges on the roof sheets. The ridge seam covers are cut away at the sides where their flanges approach the side marginal flanges of the roof sheets, and the tops of the ridge seam covers are extended at the ends to meet at about above the center lines of the carlines. The extended ends of the ridge seam covers and the ridge corner caps have alining holes 29 punched through them and through the top web of the ridge piece through which pass bolts 30 which secure the wooden running board saddles 31, supported crosswise upon the ridge piece over the carlines. The ends of the running board saddles rest on the side seam covers above the carlines, and are partly supported thereby. Metal plates 32 are placed over the running board saddles

to prevent water from passing through the bolt holes and into the car, and upon these plates the running boards 33 are arranged and secured to the saddles by nails or other suitable fastening means.

The modified forms of roof sheet and seam cover shown in Figs. 10 to 13, inclusive, are particularly well suited for meeting the requirements of hard service. The roof sheets 34 are made from corrugated sheet metal, and are formed with upstanding side flanges 35 and ridge flanges 36 provided with rebent marginal lips 37 and solid corners 38 in the manner already described with reference to the roof sheets 11. The corrugations are flattened out at the eaves ends of the sheets, and these ends are turned down to form eaves flanges 39. The roof sheets are dished between their side flanges, that is, the portions 40 of the sheets adjacent to the side flanges are inclined upwardly to where they join the bases of the side flanges. The seam covers 41 have downwardly and outwardly inclined sides 42, as in the form shown in Figs. 1 to 9, and are provided with lateral base flanges 43 conforming to the slant of the marginal portions 40 of the roof sheets. The lateral base flanges 43 of the seam covers press down on the slanting marginal portions 40 of the roof sheets between the corrugations and side flanges of the roof sheets, and form substantially water tight resilient joints. Spacing the slanting marginal or dished portions of the roof sheets above the substructure eliminates any trouble due to the seam covers pinching the roof sheets down on the substructure and preventing the slight shifting of the roof sheets to accommodate themselves to distortion of the substructure. There is sufficient spring in the seam cover flanges and in the upwardly inclined marginal portions of the roof sheets to keep them in close contact at all times, and to maintain the tightness of the joint even though the roof sheets may become displaced from their normal positions. Moreover, the pressure of the seam covers on the inclined marginal portions of the sheets has a tendency to maintain the sheets in their normal positions. This shape and arrangement of seam covers and roof sheets not only provides a water tight seam or joint between adjacent roof sheets well adapted to prevent the entering of water into the car, and one in which water and cinders will not collect, but also provides a flexible means for retaining the sheets in normal position on the car.

The eaves ends 44 of the side seam covers are turned down over the eaves, covering the ends of the carlines and the eaves corners of the roof sheets, and are spaced away from the fasciae sufficiently to allow slight freedom of movement of the corners of the roof sheets crosswise of the roof. The

10 downturned ends of the seam covers are loosely secured to the side of the car by bolts 45 which also attach the fasciae to the side plates. The bolts 45 pass through holes in the ends of the seam covers larger than the bolts, and bushings 46 are placed on the ends of the bolts between the fastening nuts 47 and fascia for the purpose of spacing the nuts from the fascia and allowing freedom of movement of the seam covers crosswise of the car.

15 With the exception of the running board saddles and running boards my roof is made entirely of metal, preferably steel, forming a light, stiff, water tight structure of shallow depth, in which all parts are readily inspected and easy to remove and replace without dismantling the entire roof. The roof sheets are very securely held in place by the ridge and seam covers and eaves caps and clips and yet are not rigidly secured to the substructure, and may be removed and replaced without difficulty by removing the adjacent ridge and seam covers 20 and eaves caps and clips. The thickness of the roof sheets and spacing of the purlins with respect to the ridge piece and side plates are such that the sheets will support the weight of a man without deflecting unduly, and thus no wooden roof sheathing need be used, either to support the roof sheets as in the "outside" metal roof, or to protect them as in the "inside" metal roof, as made heretofore.

25 35 I believe myself to be the first to construct a metal car roof having the advantages above set forth, and therefore do not wish to be limited to the precise details of construction disclosed herein, but claim and desire to secure by Letters Patent a metal car roof having the essential characteristics of my invention.

40 What I claim is:

1. A car roof comprising carlines having lateral flanges projecting from their sides below their tops, purlins secured to and projecting above said lateral flanges with their tops below the tops of the carlines, a ridge piece arranged on the tops of said carlines and secured thereto and having lateral flanges projecting from its sides below their tops, and roof sheets having upturned marginal flanges on three edges supported on said purlins and on the flanges of said 45 ridge piece between the carlines with their marginal flanges arranged adjacent to the sides of said carlines and ridge piece and below the planes of the top thereof, respectively.

50 60 2. A car roof comprising a substructure, metal roof sheets thereon extending from the eaves toward the ridge, metal seam covers overlying the adjacent side margins of said sheets without binding said sheets and means for loosely securing the same

70 to the roof substructure at the ridge, metal ridge covers overlying the adjacent ridge margins of said sheets without binding said sheets and means for rigidly securing the same to the roof substructure, said sheets being provided with upstanding flanges at their side and ridge margins and with upstanding corrugations adjacent to the side margins, said seam covers and ridge covers being longitudinally formed to receive said 75 flanges beneath the same and out of contact therewith, the sides of said seam and ridge covers terminating in flanges resting on said sheets between the said marginal corrugations and flanges.

80 3. A car roof comprising a substructure, metal roof sheets thereon extending from the eaves toward the ridge, metal seam covers overlying the adjacent side margins of said sheets and means for loosely securing the same to the roof substructure at the ridge, metal ridge covers overlying the adjacent ridge margins of said sheets, and means for rigidly securing the same to the roof substructure, said sheets being provided with upstanding flanges at their side and ridge margins and with upstanding corrugations adjacent to the side margins, said seam covers and ridge covers being longitudinally formed to receive said 90 flanges beneath the same, the sides of said seam and ridge covers terminating in flanges resting on said sheets between the said marginal corrugations and flanges.

95 4. A car roof comprising a substructure, metal roof sheets thereon extending from the eaves toward the ridge, metal seam covers overlying the adjacent side margins of said sheets without binding said sheets and means for loosely securing the same to the roof substructure at the ridge, metal ridge covers overlying the adjacent ridge margins of said sheets without binding said sheets and means for rigidly securing the same to the roof substructure, said sheets being provided with upstanding flanges at their side and ridge margins and with upstanding corrugations adjacent to the side margins, said seam covers and ridge covers being longitudinally formed to receive said 100 flanges beneath the same and out of contact therewith, the sides of said seam and ridge covers terminating in flanges resting on said sheets between the said marginal corrugations and flanges.

105 115 5. In a car roof, a substructure comprising metal carlines supported on the side plates, a continuous metal ridge piece having lateral base flanges supported on said carlines and purlins extending lengthwise of said car beneath said carlines, in combination with roof sheets extending between said carlines from the eaves toward the ridge and supported on said purlins and on said ridge piece flanges, said roof sheets 120 125 130

being contained within the vertical space limits of said substructure.

6. In a car roof, a substructure comprising metal carlines supported on the side plates, a continuous ridge piece supported on said carlines, and purlins extending lengthwise of said car supported on said carlines, in combination with roof sheets extending from the eaves toward the ridge and supported on said purlins and on said ridge piece, ridge covers extending from carline to carline and resting flatwise on said substructure and having downwardly extending sides terminating adjacent to said roof sheets and adapted to coöperate therewith to retain the latter in position, spaced means for rigidly securing said ridge covers upon said substructure, and cover caps having intersecting channels for said ridge covers and carlines and also secured by said means.

7. In an all metal car roof, channel carlines arranged with the sides downward, said carlines having flanges parallel with the top webs along the bottoms of the sides thereof projecting laterally, a ridge piece of substantially the same shape in cross section as said carlines, said ridge piece being secured on the top webs of the carlines with its lateral flanges in contact therewith, metal roof sheets extending from the ridge piece to the eaves between the carlines, said roof sheets resting on the lateral flanges of the ridge piece and having side flanges arranged adjacent to the sides of the carlines within the vertical space limits of said carlines and ridge piece.

8. In an all metal car roof, metal carlines having substantially straight horizontal central portions and substantially straight end portions at an angle therewith sloping downward toward the eaves, said carlines being of channel section arranged with the sides downward, said carlines having flanges parallel with the top webs along the bottoms of the sides thereof projecting laterally, a ridge piece of substantially the same shape in cross-section as said carlines, said ridge piece being secured on the top webs of the carlines with its lateral flanges in contact therewith, and metal roof sheets extending from the ridge piece to the eaves between the carlines, said roof sheets resting on the lateral flanges of the ridge piece and having side flanges arranged adjacent to the sides of the carlines within the vertical space limits of said carlines and ridge piece.

9. In an all metal car roof, metal carlines having substantially straight horizontal central portions and substantially straight end portions at an angle therewith sloping downward toward the eaves, said carlines being of channel section arranged with the sides downward, said carlines having flanges par-

allel with the top webs along the bottoms of the sides thereof projecting laterally, a ridge piece of substantially the same shape in cross section as said carlines, said ridge piece being secured on the top webs of the carlines with its lateral flanges in contact therewith, and metal roof sheets extending from the ridge piece to the eaves between the carlines, said roof sheets resting on the lateral flanges of the ridge piece and having side flanges arranged adjacent to the sides of the carlines but spaced above the lateral flanges thereof and below the top webs of said carline end portions and ridge piece.

10. In an all metal car roof, channel carlines arranged with the sides downward, said carlines having flanges parallel with the top webs along the bottoms of the sides thereof projecting laterally, a ridge piece of substantially the same shape in cross section as said carlines, said ridge piece being secured on the top webs of the carlines with its lateral flanges in contact therewith, metal roof sheets extending from the ridge piece to the eaves between the carlines, said roof sheets resting on the lateral flanges of the ridge piece and having side flanges arranged adjacent to the sides of the carlines and seam covers supported on said carlines and ridge piece and overlying the margins of said roof sheets.

11. In an all metal car roof, carlines having flat tops, a ridge piece of inverted channel shape in cross-section and having lateral flanges along its sides, said ridge piece being secured on the flat tops of the carlines metal roof sheets slanting downwardly from the ridge piece to the eaves between the carlines, said roof sheets resting on the lateral flanges of the ridge piece and terminating in flanges which are arranged adjacent to the sides of the ridge piece below its top, and seam covers supported on said ridge piece and overlying the margins of said roof sheets, said seam covers having downwardly extending sides terminating in flanges resting on said slanting roof sheets adjacent to and spaced from said roof sheet flanges.

12. In an all metal car roof, metal carlines arranged with their ends slanting downward, and supported on the side plates, said carlines having top webs, a ridge piece having flanges along the bottoms of the sides thereof projecting laterally, said ridge piece being secured on the top webs of the carlines with its lateral flanges in contact therewith, metal roof sheets extending from the ridge piece to the eaves between the carlines, said roof sheets resting on the lateral flanges of the ridge piece and having upstanding side and end flanges arranged adjacent to the sides of the carlines and ridge piece, respectively, and seam covers supported on said carlines and ridge piece and overlying the

margins of said roof sheets, said seam covers having downwardly extending sides adapted to contact with the roof sheets adjacent the marginal flanges thereof.

- 5 13. In a car roof, a substructure comprising metal carlines supported on the side plates and purlins extending lengthwise of said car supported on said carlines, in combination with roof sheets extending from the 10 eaves toward the ridge and supported on said purlins, ridge covers extending from carline to carline and resting on the substructure and having downwardly extending sides terminating adjacent to said roof sheets 15 and adapted to coöperate therewith to retain the latter in position, and means for rigidly securing the ends of said ridge covers to the substructure at said carlines, whereby said sheets are maintained in alinement with the 20 portions of the ridge adjacent to their ends respectively.

14. In a car roof, a substructure comprising metal carlines supported on the side plates, and purlins extending lengthwise of 25 said car supported on said carlines, in combination with roof sheets having side and end flanges and extending from the eaves toward the ridge and supported on said purlins, ridge covers extending from carline to 30 carline and resting on the substructure and

having downwardly extending sides terminating adjacent to said roof sheets beside the end flanges thereof and adapted to coöperate therewith to retain the latter in position, means for rigidly securing the ends of 35 said ridge covers to the substructure at said carlines, and corner caps having intersecting channels for said ridge covers and roof sheet flanges and also secured by said means.

15. A flexible plate-car-roof comprising 40 an openwork substructure, load sustaining roof sheets loose thereon, said roof sheets being arranged side by side in two rows on opposite sides of the ridge, metal seam covers overlying the adjacent side margins of 45 said roof sheets without binding said sheets, metal ridge covers secured to the ridge and coöoperating with the ridge ends of the roof sheets for securing them in position, and means for rigidly securing said ridge covers 50 and loosely securing said seam covers at the ridge, whereby the roof sheets are maintained in alinement at the ridge irrespective of the distortion of the substructure.

Signed at Chicago Ill., this 19th day of 55 December, 1911.
